LADY'S COMPACT

John W. Pfrommer, Cheshire, Conn., assignor to The International Silver Company, Meriden, Conn., a corporation of Connecticut

Filed Oct. 21, 1968, Ser. No. 14,101

Term of patent 14 years

Int. Cl. D28—02

U.S. Cl. D86—1

FIG. 1 is a top perspective view of a lady's compact showing my new design; the side opposite thereto being substantially plain and unornamented;

FIG. 2 is a top plan view of the lady's compact;

FIG. 3 is a front elevational view thereof; and

FIG. 4 is a side elevational view.

I claim:

The ornamental design for a lady's compact, substantially as shown.
